(57) CLAIM

The ornamental design for a mobile device module, substantially as shown and described.

DESCRIPTION

FIG. 1 is a perspective rear view of a first embodiment of a mobile device module.

FIG. 2 is a rear view of the embodiment of FIG. 1.

FIG. 3 is a front view of the embodiment of FIG. 1.

FIG. 4 is a left side view of the embodiment of FIG. 1.

FIG. 5 is a right side view of the embodiment of FIG. 1.

FIG. 6 is a bottom view of the embodiment of FIG. 1.

FIG. 7 is a top view of the embodiment of FIG. 1.

FIG. 8 is a perspective rear view of a second embodiment of a mobile device module.

FIG. 9 is a rear view of the embodiment of FIG. 8.

FIG. 10 is a front view of the embodiment of FIG. 8.

FIG. 11 is a left side view of the embodiment of FIG. 8.

FIG. 12 is a right side view of the embodiment of FIG. 8.

FIG. 13 is a bottom view of the embodiment of FIG. 8; and,

FIG. 14 is a top view of the embodiment of FIG. 8.

The claimed design is illustrated in these two examples as a module of a handheld electronic device, such as of a mobile telephone or tablet. The design features square modules for a modular mobile telephone. The two examples illustrate common features of the design, including an arrangement of contacts in an array, a profile of side edges extending around the perimeter of the module, and a general outer shape of the module.

Broken lines and entirely unshaded portions contained within broken line are not claimed.
